[57] CLAIM

The ornamental design for play equipment including a horizontal cylinder for crawling, as shown and described.

DESCRIPTION

FIG. 1 is a perspective view of play equipment including a horizontal cylinder for crawling showing our new design;

FIG. 2 is a top plan view thereof;

FIG. 3 is a front elevation view thereof which is a mirror image of the rear elevation view thereof; and,

FIG. 4 is right side elevation view thereof that is a mirror image of the left side elevation view thereof.

FIG. 1

FIG. 2

FIG. 3

FIG. 4
